C. H. VOGEL.

TYPE WRITING MACHINE.

APPLICATION FILED FEB. 20, 1911.

1,079,731.

Patented Nov. 25, 1913.

FIG. 1.

UNITED STATES PATENT OFFICE.

CHARLES HERMAN VOGEL, OF VANCOUVER, BRITISH COLUMBIA, CANADA, ASSIGNOR
TO UNDERWOOD TYPEWRITER COMPANY, OF NEW YORK, N. Y., A CORPORATION
OF DELAWARE.

TYPE-WRITING MACHINE.

1,079,731.

Specification of Letters Patent.

Patented Nov. 25, 1913.

Application filed February 20, 1911. Serial No. 609,700.

To all whom it may concern:

Be it known that I, CHARLES HERMAN VOGEL, a British subject, residing at Vancouver, county of Vancouver, Province of British Columbia, in the Dominion of Canada, have invented new and useful Improvements in Type-Writing Machines, of which the following is a specification.

This invention relates to the carriage control of typewriting machines, and its principal object is to provide improved means for placing the carriage normally under tension, so as to advance it in its letter feeding movement by coöperating with the escapement, and for enabling the carriage to be returned at the will of the operator from any point in a line.

A further object of the invention is to provide improved margin stops for limiting the travel of the carriage, and also to provide improved means for producing the line-space movement of the platen simultaneously with the return movement of the carriage.

In carrying out my invention, I provide a cylinder which is preferably connected to the typewriter frame with its longitudinal axis parallel to the line of travel of the typewriter carriage. A piston rod passes through this cylinder, and extends beyond the ends thereof, the ends of the said piston rod having brackets or cross heads attached thereto. The piston is preferably connected to the carriage either directly or indirectly so that as the piston advances, the carriage will be advanced. The cylinder may have movable cylinder heads which limit the relative movement of the piston and cylinder and may be adjusted so as to give the effect of adjustable margin stops.

A valve normally admits an operating fluid such as air, on that side of the piston which causes the carriage to advance in the letter-feeding movement. By depressing a key, this valve may be thrown to a reverse position to admit air on the opposite side of the piston and return the carriage. As the piston reaches either of the cylinder heads, the exhaust of the air is preferably cut off, so that a desirable cushioning effect is produced. The line-space movement of the platen is preferably effected by means of a pneumatic cylinder, the piston of which is connected with the line-space wheel and is actuated by compressed air controlled preferably by the aforesaid valve, and the ar-

rangement is such that when air is admitted to the end of the carriage-controlling cylinder, it is also admitted to the line-space cylinder; so that the line-space movement and the return movement of the carriage takes place simultaneously.

Other objects and advantages will hereinafter appear.

In the accompanying drawings, Figure 1 is a longitudinal section through the pneumatic cylinder, looking from the front, illustrating the manner of mounting the same, and showing also the means for attaching it to the carriage. Fig. 2 is a side view largely sectional showing the invention as combined with an Underwood typewriting machine. Fig. 3 is a longitudinal section through a pneumatic cylinder, showing a modified form of the invention referred to above, in which the cylinder moves instead of the piston. Fig. 4 shows a portion of the end of the typewriter carriage, and shows the pneumatic line-space cylinder in vertical section.

On the base 20 supporting the typewriting machine, brackets 19 are provided to support a pneumatic cylinder 1 with its axis horizontal and parallel to the direction of movement of the carriage. Within this cylinder, a piston head 2 is provided on a rod 3. This rod passes through the piston and extends through movable stops 4 which form the heads of the cylinder. Beyond the heads 4, the ends of the piston rod 3 are provided with rigid cross arms 29, which extend laterally and carry a rigid guide bar 30, which is parallel to the axis of the cylinder, and is guided in suitable guide brackets 36 which extend up from said brackets 19. These members 36 guide the piston and piston rod as the piston moves to and fro in the cylinder.

The brackets or cross arms 29 are preferably provided with sheaves or pulleys 31 and cords 32, which are attached to each end of the cylinder, pass around these sheaves and are attached to a double link 33 which may be attached to a lug 100 on the carriage 101 through the medium of a central opening 34. The cord at the left is not attached directly to this link 33, but is attached through the medium of a spring 35, and a turn buckle 102 may be interposed in the cord to take up lost motion. With this arrangement, when the piston head 2 is forced to the left, the link 33 will also be moved

toward the left, and move the carriage in the letter-feeding direction. On account of the arrangement of the cords 32 and sheaves 31, it will be evident that the carriage will have twice the amount of movement of the piston head.

- In order to control the piston, I provide an air-chest 9 into which compressed air is admitted through a nipple 10, and this air is controlled by an admission valve 11 having a stem 14 connected with lever 15 and rock shaft 16, which enables the valve to be moved by depressing a key 17, which is attached to the rock shaft, as shown.
- 15 A return spring 18 under the key 17 normally holds the valve 11 in the Fig. 1 position, so that air will be admitted through the right hand port 5^a and flexible hose 5, and through the cylinder head 4, passing a check valve 6, which opens toward the interior of the cylinder. The port opening through the cylinder head 4 adjacent to the valve 6 may be regulated by a set screw 37. In this way tension is normally erected on 20 the carriage which advances it in the letter-feeding movement when the escapement operates.
- 25 At the will of the operator, by depressing the key 17, the valve 11 will be reversed, admitting air through left port 5^a, reversing the air pressure on the piston 2, and forcing it toward the right. The air in the right end of the cylinder is expelled through the port 7^a, which will then be connected with 30 the exhaust outlet 12.

- 35 As the piston 2 is approaching the right cylinder head in the return movement, the air before it is expelled through an exhaust port 4^a which connects with a flexible hose 40 7, said hose being connected with a port 7^a in the cylinder wall opening onto the valve seat. The port 4^a extends through the head 4 from the inner end of a pocket 4^b formed in the inner face of the cylinder head, and a 45 boss 2^a is formed on the piston face which plugs this pocket as the piston reaches the end of its stroke. As the boss 2^a enters the pocket 4^b, the exhaust flow of air through the port 4^a is cut off, and the air which is 50 thus caught in this end of the cylinder becomes compressed, and gives a cushion effect in arresting the piston. This air cannot escape through the check valve 6, as the increased pressure simply forces it more firmly 55 upon its seat. In order to regulate the flow through the port 4^a, a set screw 8 is provided in the cylinder head.

- 60 In order to adjust the position of the cylinder heads 4 to vary the point at which the carriage will stop in its travel, each cylinder head is provided with a pair of racks 21, which mesh with pinions 22 carried on a transverse shaft 23, and rotatable by means of a hand-wheel 24. At the inner end of the 65 shaft 23, a locking disk 25 is provided with

a plurality of perforations 25^a, disposed equidistant and adapted to align with a locking pin 26. A spring 28 around the shaft 23, normally holds one of the perforations 25^a of the disk 25 in engagement with the pin, as shown in Fig. 2.

70 When a new adjustment is desired, the operator presses the hand-wheel 24 inwardly to disengage the disk 25 from the pin, and the shaft should then be rotated so as to move the racks 21 through the medium of the pinions 22 into any position desired. When the hand-wheel 24 is released, it should be held so that one of the openings 25^a will register with the pin 26, and this holds the cylinder head fixed. On the forward side of one of the racks 21 a scale is formed, as indicated in Fig. 1, which enables the width of the margin on the paper to be ascertained at a glance.

75 It should be understood that the parts on the right of center line C, Fig. 1, that is, the cylinder heads and the adjusting devices therefor, and the air hose connections, together with the air passages, are duplicated 80 at the other end of the cylinder.

85 Instead of having the pneumatic cylinder fixed, I may let the cylinder move, and I then provide a pair of fixed pistons within the cylinder, as illustrated in Fig. 3; where- 90 in 41 represents the cylinder, through the heads 52 of which tubular piston rods 43 and 51 pass. The tubular piston rod 43 is attached to the piston head 42, and the interior of the rod communicates with a port 46 which leads back through an inwardly opening check valve 45, so as to admit air in the right-hand end of the cylinder.

95 Near the extreme end of the tube 43, a port 44 is provided through the wall of the tube which permits air to flow directly from the tubular rod 43 into the right end of the cylinder. A similar construction is provided in connection with the other piston head 47, that is, it is provided with a port 100 48 communicating with the interior of the piston rod 51, and leading back through a check valve 49, so as to admit air to the left end of the cylinder; and this rod 51 is provided with a port 50 in its wall, through 105 which air may flow directly into the left end of the cylinder. The cylinder may be connected with the carriage as in the preferred form of the invention, or in any desired manner.

110 When compressed air is admitted to the tubular rod 43, with the cylinder in the Fig. 3 position, it flows into the end of the cylinder through the port 44, and drives the cylinder toward the right to return the carriage. Air is normally admitted to the left end of the cylinder, and tends to move the cylinder toward the left to give the carriage 115 its line-feeding movement. As the cylinder approaches the limit of its travel, in either 120 125 130

direction, a cushion effect results, by reason of the ports 44 and 50. Suppose that the cylinder is moving toward the left, and the air is being expelled from the right end of the cylinder, as the cylinder advances. As the head 52 covers the port 44, the exhaust of the air ceases and no further exhaust can take place. This air is therefore caught in the cylinder and compressed, giving the effect of a cushion. When air is admitted through the tubular rod 43, it can always pass to the interior of the cylinder through the check valve 45, and will initiate a return movement of the carriage; as soon as the port 44 is uncovered, an increased flow of air into the cylinder takes place.

Although I have described compressed air as the operating medium, it is obvious that any compressed gas or fluid may be used instead of compressed air, and instead of using compressed air, I may operate the mechanism by creating a vacuum or partial vacuum, and produce the motive force by atmospheric pressure.

I prefer to locate the key for operating this mechanism at a convenient point near or at the keyboard.

The spring 35 keeps the cords 32 taut and gives a desirable elasticity, permitting the piston 2 to run "ahead" of the carriage, so that the spring draws the carriage in coöperating with the escapement. In this way, the spring absorbs the momentum of the piston and its connected parts. The cord may be provided with a turn buckle 102 if desired, and this turn buckle by adjusting the tension of the cord 32 will adjust the tension of the spring 35.

In order to produce the line-space movement of the platen, a pneumatic cylinder 55 is attached on the end 54 of the carriage by means of a pivot screw 58. This cylinder is disposed in a substantially horizontal position and within it a piston 56 travels, said piston being preferably hollow, and having an extension or rack 56^a, which is provided with inclined rack teeth 63, which engage corresponding teeth of a line-space wheel 64, which is rigid on the platen axle 64^a. The large hollow dead space in piston 56 compared with the restricted inlet prevents the full pressure of the fluid from pressing the piston at once, so it starts slowly, and so is less likely to tear any thin work sheets which may lie against the platen.

The end of the cylinder 55, remote from the line-space wheel, is provided with a nipple 61, and this nipple is connected by a flexible hose 13^a with a nipple 13, which communicates with the left port 5^a in the cylinder 1, and which leads to the left end of the cylinder. From this arrangement, when the valve 11 is moved to the right, to uncover the port 5^a and admit air to air chest 9, a portion of this air flows through

the hose 13^a into the cylinder 55, and forces the piston 56 outwardly. The teeth 63 then engage the teeth of the line-space wheel and give the same a partial rotation. As soon as the valve 11 returns to the Fig. 1 position, the air within the cylinder 55 flows back through the hose 13^a and through left port 5^a into the left end of the cylinder 1, from which it escapes through the left port 7^a and the exhaust outlet 12.

The cylinder 55 is normally held up by a spring 60, so as to keep the rack 56^a yieldingly in engagement with the line-space wheel. When the air is exhausted from the cylinder 55, the piston 56 is returned to the Fig. 4 position by a return spring 57, and as the teeth 63 slip over the teeth of the line-space wheel 64, a slight lateral vibration of the cylinder and piston takes place on a pivot 58 as an axis. A stop pin 59 above the cylinder limits the upward movement of the cylinder by the spring.

Near the end of the cylinder 55, adjacent the platen, a stop 62 is pivotally mounted, said stop having three shoulders 62^a, any one of which may be interposed in the path of the end of the piston so as to limit the outward movement of the piston. In this way, the amount of rotation given to the line-space wheel is adjusted.

In Fig. 2 the invention is shown as applied to an Underwood typewriting machine, which includes a carriage 101 sliding on a guide 103 and carrying a lug 100, which lug engages the link 33. Said carriage is drawn along by the piston 2 through said link, and in letter-feeding direction is controlled by means of an escapement wheel 104, said escapement wheel being controlled in the usual manner by type keys 105, which, through bell cranks 106, swing type bars 107 upwardly and rearwardly, so that heels 108 on said type bars actuate a universal member 109. Said escapement wheel 104 is controlled from said universal member by means of dogs 110 and 111, which are actuated by said universal member.

Variations may be resorted to within the scope of the invention, and portions of the improvements may be used without others.

Having thus described my invention, I claim:

1. In a typewriting machine, a pneumatic cylinder, a piston movable with respect to said cylinder, means connecting said cylinder and said piston to the typewriter carriage to move the same when a relative movement occurs between said piston and said cylinder, means for admitting an operating medium to one end of said cylinder, and a stop in the path of said piston to arrest it and adapted to cushion the movement thereof by trapping the fluid in the cylinder.

2. In a typewriting machine, in combina-

- tion, a pneumatic cylinder, a piston movable therein, means for connecting said piston and said cylinder to the carriage to move the carriage in each direction, and 5 adjustable cylinder heads in said cylinder limiting the movement of said piston.
3. In a typewriting machine, a pneumatic cylinder, a piston movable therein, means for connecting said piston and said cylinder 10 with the typewriter carriage to move the same, cylinder heads movably mounted in said cylinder and limiting the movement of said piston, means for admitting an operating fluid to said cylinder, means permitting the escape of said operating fluid before said piston, as the same advances, and means for closing said last means to form a cushion before said piston, in arresting the movement thereof.
- 20 4. In a typewriting machine, a pneumatic cylinder, a piston movable therein, mechanism connecting said cylinder and said piston with the carriage to move the carriage, movable heads in said cylinder limiting the movement of said piston, and means for admitting air into the interior of said cylinder through said heads.
- 30 5. In a typewriting machine, a cylinder, a piston moving therein, said cylinder having an exhaust port for the operating medium, and means forming an extension of said piston for closing said port before said piston reaches the end of the stroke to form a cushion in advance thereof.
- 35 6. In a typewriting machine, a pneumatic cylinder having a head with a pocket on the inner face thereof, a piston moving within said cylinder, and having a boss adapted to enter said pocket, said head having an exhaust port within said pocket adapted to lead the operating fluid from the interior of said cylinder, said piston having a boss on the face thereof adapted to enter said pocket to cut off outlet from said cylinder through 40 said port, thereby cushioning said piston at the end of said stroke.
- 45 7. In a typewriting machine, the combination with a traveling carriage, of a cylinder and a piston therein, means for admitting fluid to said cylinder to cause relative movement between said carriage and typewriter, a movable head comprising a cushioning member in said cylinder, a rack for adjusting said head, and a stop holding said 50 rack.
- 55 8. In a typewriting machine, the combination with a traveling carriage, of a cylinder and a piston therein, means for admitting fluid to said cylinder to cause relative movement between said cylinder and piston, a cord fast to said carriage and fast to a fixed point on said frame, and a pulley moving with said movable member about which said cord passes to move said carriage.
- 60 9. In a typewriting machine, the combination with a traveling carriage, of a cylinder and a piston therein, means for admitting fluid to said cylinder to cause relative movement between said cylinder and piston, a cord fast to said carriage and fast to a fixed point on said frame, and a pulley moving with said movable member about which said cord passes to move said carriage.
- 65 10. In a typewriting machine, the combination with a traveling carriage, of a cylinder and a piston therein, means for admitting fluid to said cylinder to cause relative movement between said cylinder and piston, a cord fast to said carriage and fast to a fixed point on said frame, and a pulley moving with said movable member about which said cord passes to move said carriage.

nation with a traveling carriage, of a fluid operated cylinder for returning said carriage at the end of a line, a separate cylinder for operating a line-space mechanism, and a single valve for both cylinders.

10. In a typewriting machine, the combination with a traveling carriage, of a cylinder and a piston therein, means for admitting fluid to said cylinder to cause relative movement between said carriage and typewriter, a movable head in said cylinder, a rack carried by said head, a pinion in mesh with said rack, and a stop on said machine arranged to be engaged by a wheel fast on said pinion to hold said cylinder head adjusted.

11. In a typewriting machine, the combination with a traveling carriage, of a cylinder and a piston therein for driving said carriage by a compressible fluid and arranged to start said carriage rapidly, and a fluid operated line-spacing mechanism arranged to operate said line-spacing mechanism slowly.

12. In a typewriting machine, the combination with a traveling carriage, of a cylinder and a piston therein for driving said carriage by a compressible fluid and arranged to start said carriage rapidly, a fluid operated line-spacing mechanism arranged to operate said line-spacing mechanism slowly, and a single valve controlling both carriage return and line spacing mechanisms.

13. In a typewriting machine, the combination with a traveling carriage, of a pneumatic cylinder, a piston in said cylinder, an opening for admitting compressed air to said cylinder, a check valve in said opening for preventing the outflow of air, an exhaust opening for said cylinder, and a valve controlling said admission opening and said exhaust opening.

14. In a typewriting machine, the combination with a traveling carriage and a pneumatic cylinder, of a piston traveling in said cylinder, an opening for admitting compressed air to said cylinder, a check valve in said opening, an exhaust port for said cylinder so arranged with reference to said piston that at the end of the traveling of said piston, exhaust through said exhaust port is hindered, whereby the piston is cushioned when arrested.

15. In a typewriting machine, the combination with a traveling carriage and a pneumatic cylinder, of a piston traveling in said cylinder, a head adjustable in said cylinder for limiting the travel of said piston, a rack fast on said head, a pinion meshing with said rack, and a hand wheel for turning said pinion to adjust said head.

16. In a typewriting machine, the combination with a traveling carriage and a pneumatic cylinder, of a piston in said cylinder,

a head adjustable in said cylinder, a rack fast on said cylinder comprising a scale, a pinion comprising a hand wheel meshing with said rack, and a detent for holding said

5 hand wheel in its adjusted position.

17. In a typewriting machine, the combination with a traveling carriage and a cylinder, of a head adjustable in said cylinder, two racks on said head, pinions meshing

10 with said racks, a shaft on which said pinions are fast, and a hand wheel fast on said shaft.

18. In a typewriting machine, the combination with a cylinder, of a piston therein, a piston rod extending from each end of said cylinder, a frame carried by the ends of said piston rod, pulleys carried on said frame, and a belt passing around said pulleys for driving the carriage.
